BRIDGING PLUG AND SETTING TOOL
THEREFOR

Arthur J. Zschokke, Huntington Park, Calif., assignor to The Technicraft Engineering Corp., Los Angeles, Calif., a corporation of California

Application July 15, 1935, Serial No. 31,392

11 Claims. (Cl. 166—13)

My invention relates to bridging plugs and setting tools therefor, and the objects of my invention are:

First, to provide a novelly coacting bridging plug and setting tool wherein the setting tool not only manipulates the plug but also supplies the force required to set the plug in sealing relation with the well bore;

Second, to provide a setting tool which is hydraulically operated and may be associated with either a tubing string or special pump mechanism adapted to be lowered with the setting tool on a cable;

Third, to provide a bridging plug which is particularly economical of manufacture and which may be constructed for the most part from friable material such as cast iron so that the plug may be cemented in place and left permanently unless it should be desirable to deepen the well, in which event, the plug may be drilled up with the cement;

Fourth, to provide a bridging plug and setting tool therefor which incorporates a novel releasable connecting means so arranged that the setting tool is automatically disconnected from the bridging plug after the setting tool has performed its function of securing the bridging plug in position;

Fifth, to provide a bridging plug which incorporates a novel clutch mechanism designed to hold the parts of the plug in their set or well engaging position to which they have been forced by the setting tool, said clutch being protected from accidental release such as by mechanical engagement with a well tool on top of the plug;

Sixth, to provide a bridging plug incorporating a clutch mechanism which may be arranged for engagement by a special releasing tool such as disclosed in my copending application Serial No. 31,391, filed July 15, 1935, whereby the clutch mechanism may be rendered inoperative and the plug released for removal from the well bore; and,

Seventh, to provide a novel electro-hydraulic manipulating tool which is adapted to utilize the surrounding well fluid as a pressure medium, whereby the hydrostatic head of the well fluid in no manner interferes with the operation of the tool or requires excessive pressure differences between the low and high sides of the hydraulic elements of the tool.

With these and other objects in view as may appear hereinafter, reference is made to the accompanying drawings, in which:

Fig. 1 is an elevational view of my bridging plug

shown in its released or free position and attached to one form of my setting tool therefor, in which the setting tool is supported and operated from a cable.

Fig. 2 is an enlarged, fragmentary, longitudinal, and sectional view thereof taken substantially through 2—2 of Fig. 1, showing the setting tool and its connection with the bridging plug.

Fig. 3 is a similar sectional view showing the bridging plug and continuing from Fig. 2, the view being taken substantially through 3—3 of Fig. 1 and indicating by dotted lines the set position of the bridging plug.

Fig. 4 is a fragmentary longitudinal sectional view similar to Fig. 2 showing in solid lines the connection between the setting tool and plug upon setting the plug and as the plug is being released, and showing by dotted lines the arrangement of the parts of the setting tool after the plug has been fully released.

Fig. 5 is a transverse sectional view through 5—5 of Fig. 2 showing the gear pump.

Fig. 6 is a transverse sectional view through 6—6 of Fig. 2 showing the setting tool clutch which causes the setting tool to disengage from the bridging plug when the operating element of the tool returns to its normal position.

Fig. 7 is a transverse sectional view through 7—7 of Fig. 2 showing the top of the bridging plug in elevation.

Fig. 8 is a transverse sectional view through 8—8 of Fig. 2 showing particularly the clutch mechanism of the bridging plug and the releasable connection between the plug and setting tool.

Fig. 9 is a fragmentary elevational view similar to Fig. 1 but partially in section, showing a modified form of setting tool adapted to be supported from a tubing string and operated in response to hydrostatic pressure applied through the tubing string.

The herein described bridging plug as illustrated best in Figs. 1, 2, 3, 4, and 8 is built up around a tubular body member 1 of uniform diameter which is screwthreaded at its lower end to receive a packer body 2.

The packer body comprises a cylindrical upper portion 2a somewhat larger in diameter than the body member 1 and which is adapted to receive a packing member 3 which may be in the form of a sleeve with its bore beveled at its upper and lower ends. Below its cylindrical portion 2a, the packer body 2 is enlarged in diameter to conform to the bevel of the lower end of the packing member for expanding the same as indicated by 2b. The lower end of the packer body is closed.

55

Above the packer body 2, the body member 1 receives a slower slip expanding cone 4. Said cone comprises an elongated frusto-conical slip expanding surface 4a, terminating at its upper end in a flange 4b which is undercut at its under side. An annular rib 1a formed on the body member engages the upper end of the cone to limit upward movement thereof. The lower part of the cone 4 is enlarged internally to fit over the cylindrical portion of the packer body 2 and is beveled at its lower extremity, as indicated by 4c to engage the upper end of the packing member 3.

As shown, the packing member is expanded 15 into its sealing position such as shown in Fig. 3 by movement of the packer body toward the lower cone 4. Various conventional packer members whether of the sleeve or multiple ring type may be used.

20 At the upper end of the body member 1 is slidably fitted an upper slip expanding cone 5 likewise having an elongated frusto-conical slip expanding surface 5a and terminating at its lower end in a flange 5b the upper side of which is undercut. The slip expanding surfaces of the two cones converge toward each other, and are adapted to be engaged by arcuate, wedge-shaped slips 6 having teeth in their outer sides. Two sets of slips are provided, one for each cone. 25 A strap or rein 7 connects each corresponding pair of slips by their larger ends. The several reins are secured at their mid-portions to a collar 8 which slidably fits the body member 1. The portion of each rein between the collar and lower slip is preferably corrugated as indicated by 1a or otherwise rendered yieldable to compression stresses.

The upper cone 5 extends above the body member 1 and its bore is enlarged to receive a clutch 40 mechanism 9. Said clutch mechanism comprises a collar 9a which is screwthreaded on the upper end of the body member and is provided at its outer side with an upwardly diverging clutch surface 9b. Fitted between the clutch surface 45 and the surrounding wall of the upper cone 5 are a plurality of segmental clutch slips 9c, the inner sides of which slope in conformity with the clutch surface 9b and the outer sides of which are parallel with the axis of the upper cone 5 and conform to its bore. The upper ends of the clutch slips 9c overhang the upper end of the clutch collar 9a and a spring 9d is mounted therebetween to urge the clutch slips upwardly. 50 A guard ring 9e loosely rests on top of the clutch slips. Said guard ring is beveled internally at its upper side and is adapted to be engaged by a releasing tool, such as disclosed in my aforementioned copending application thereon, for the clutch mechanism.

55 The above described clutch mechanism permits the cones 4 and 5 to move toward each other and the packer body to actuate the packing member, but does not permit return movement there- 60 of; so that the bridging plug is free to assume a set position such as shown in Fig. 3 but cannot return to its released position unless the clutch mechanism is rendered inoperative.

Near its upper end the clutch collar 9a is pro- 70 vided internally with an annular groove 9f which is adapted to receive key balls of the setting tool described hereinafter.

The setting tool comprises a cylinder 11 in which is mounted a piston 12 to which is attached 75 a piston rod 13. The piston rod extends below

the cylinder and is provided with a cross-arm 14 which is adapted to engage the top of the upper cone 5. The lower end of the cylinder 11 is provided with a fitting 15 having a screw-threaded bore of reduced diameter therethrough in which is screwed the upper end of an outer sleeve 16. Within the outer sleeve is fitted an inner sleeve 17, both the sleeves are slotted at opposite sides to clear the cross-arm 14.

10 The lower ends of the sleeves extend into the clutch collar 9a and the outer sleeve is provided with a series of circumferentially spaced apertures, each of which receives a key ball 18 adapted to fit in the groove 9f provided in the clutch collar 9a. The inner sleeve 17 normally extends 15 past the key balls to retain them in position, but is adapted to be raised relative to the outer sleeve to release the key balls and thereby disconnect the setting tool from the plug.

20 The inner sleeve is supported from the piston rod 13 by a clutch mechanism 19 which may be similar in arrangement to the clutch mechanism 9. Said clutch mechanism 19 comprises a clutch ring 19a screwthreaded in the upper end of the inner sleeve 17 and having an upwardly converging inner wall or bore. Fitted within the clutch ring 19a are a plurality of segmental clutch elements 19b having correspondingly converging outer walls and adapted to fit around and engage the piston rod 13. The upper ends of the clutch elements 19b overhang the clutch ring 19a and a spring 19c is provided therebetween. The clutch ring 19a is provided with a flange at its upper end which overhangs the end of the outer sleeve 16 to limit downward movement of the inner sleeve relative thereto.

25 The clutch mechanism is so arranged that the piston rod is free to move downwardly with respect to the inner sleeve, but when the piston rod moves upwardly, the inner sleeve is pulled upwardly through the clutch mechanism and releases the key balls 18.

30 Upward or return movement of the piston rod is accomplished by a spring 20 interposed between the piston 12 and the fitting 15. The downward or operating movement of the piston rod is accomplished by the application of hydraulic pressure against the top of the piston.

35 As shown best in Fig. 2, this may be accomplished by a gear pump unit 21 which may be contained in a housing 21a secured to and closing the upper end of the cylinder 11. The gear pump is provided with a centrally disposed driving gear 21b and one or more driven or idler gears 21c. Intake ports 21d extend into the housing 21a from the outside so as to admit the well fluid. Discharge ports 21e lead from the pump downwardly through the housing and enter the cylinder 11 above the piston 12. When the pump is not operating, sufficient clearance is provided to bleed fluid from above the piston and permit its return movement.

40 A drive shaft 22 for the gear 21b extends upwardly from the housing 21a through a packing gland 23 and is suitably connected to an electric motor 24. The motor 24 is preferably provided with a cylindrical shell and is spaced from the pump unit by a pipe section 25 of sufficient length to permit a quantity of well fluid to collect therein should the packing gland 23 leak. The upper end of the electric motor 24 is joined to a cable head 26 which is provided at the end of a cable 27. The cable 27 comprises outer weight supporting strands and a central insulated conductor. 45

The cable head 26 is provided with suitable means not shown for connecting the electric motor through the cable with a source of electrical energy at the mouth of the well.

- 5 As shown in Fig. 9, the cylinder 11 may be connected through an adapter fitting 28 to a tubing string 29. By applying hydraulic pressure through the tubing string in excess of the well fluid pressure, the piston 12 may be forced down. 10 In this arrangement, bleeder ports 28a are provided in the fitting 28, so that fluid levels within and outside the tubing string may equalize and permit upward or return movement of the piston.

The bridging plug is set as follows:

- 15 The bridging plug is initially arranged as shown in Figs. 1, 2, and 3 with the hook portions of the slips 6 engaging the undercut sides of the flanges 4b and 5b; the packing member is in its normal or non-packing position; the sleeve 16 is 20 secured to the bridging plug through the clutch collar 9a and key balls 18; and the piston is in its upper position with the cross bar 14 resting on the top of the upper cone 5.

The bridging plug and setting tool are lowered, 25 either by the special cable or on tubing string, to the desired level. Hydraulic force is applied to the top of the piston, causing the cross bar or arm 14 to push down on the upper cone, or the sleeve 16 to pull upward on the body member 30 1 and packer body 2, with the result that the two cones are moved toward each other until the slips 6 engage the walls of the surrounding casting, and the packer member has been expanded into a sealing relation therewith.

- 35 After a sufficient interval has elapsed to insure the above operation, the motor is stopped. Sufficient clearance is provided between the gears of the pump to permit back flow of the fluid above the piston, or a relief port may be provided. This 40 permits the spring to return the piston to its upper or initial position. As the piston and its piston rod move upwardly, the clutch mechanism 19 grips the piston rod causing the inner sleeve 17, to clear the key balls 18 which are then 45 free to drop out as shown in Fig. 4, to disconnect the setting tool from the bridging plug.

Though I have shown and described certain embodiments of my invention, I do not wish to be limited thereto but desire to include in the scope 50 of my invention the constructions, combinations, and arrangements substantially as set forth in the appended claims.

I claim:

1. In a well tool; an implement adapted to be lowered within a well bore, and including elements adapted when moved relatively to secure the implement therein; and a setting tool for said implement, comprising: a releasable connecting device for initially supporting said implement, a hydraulically responsive means for urging said elements in a manner to secure said implement, and a releasing means for said device operative subsequently to said hydraulically responsive means to release the implement from the setting tool.

2. In a well tool; an implement adapted to be lowered within a well bore, including elements adapted when moved relatively to secure the implement therein, and an instrumentality for restraining said implement against subsequent release; and a setting tool for said implement, comprising: a releasable connecting device for initially supporting said implement, a hydraulically responsive means for urging said elements in a manner to secure said implement, and a releasing

means for said device operative subsequently to said hydraulically responsive means to release the implement from the setting tool.

3. In a well tool; an implement adapted to be lowered within a well bore, and including elements adapted when moved relatively to secure the implement therein; and a setting tool for said implement, comprising: a releasable connecting device for initially supporting said implement, operating means connected with said implement through said device for moving said elements in a manner to secure said implement within a well bore, hydraulic means for urging said operating means in one direction from an initial position, yieldable means tending to return 15 said operating means to its initial position, and an instrumentality operative upon return movement of said operating means for releasing said device and disconnecting said setting tool from 20 said implement.

4. In a well tool; an implement adapted to be lowered within a well bore, including elements adapted when moved relatively to secure the implement therein, and a clutch mechanism adapted to permit movement of said elements in a manner to secure the implement and restrain said elements against return movement; and a setting tool for said implement, comprising: a releasable connecting device for initially supporting said implement, operating means connected with said implement through said device for moving said elements in a manner to secure said implement within a well bore, hydraulic means for urging said operating means in one direction from an initial position, and yieldable means tending to return 25 30 said operating means to its initial position.

5. In a well tool; an implement adapted to be lowered within a well bore, and including elements adapted when moved relatively to secure the implement therein; and a setting tool for said implement, comprising: a releasable connecting device for initially supporting said implement, a cylinder and piston therefor connected with said implement through said device, means for supplying fluid under pressure to urge said piston in 40 45 one direction relative to said cylinder and cause movement of said elements in a manner to secure said implement, yieldable means tending to return said piston to its initial position, and an instrumentality operative upon return movement 50 of said piston for releasing said device and disconnecting said setting tool from said implement.

6. In a well tool; an implement adapted to be lowered within a well bore, including elements adapted when moved relatively to secure the implement therein, and an instrumentality for restraining said implement against subsequent release; and a setting tool for said implement, comprising: a releasable connecting device for initially supporting said implement, a cylinder and piston therefor connected with said implement through said device, means for supplying fluid under pressure to urge said piston in one direction relative to said cylinder and cause movement of said elements in a manner to secure said implements, yieldable means tending to return said piston to its initial position, and an instrumentality operative upon return movement of said piston for releasing said device and disconnecting said setting tool from said implement.

7. In a well tool; an implement adapted to be lowered within a well bore, and including elements adapted when moved relatively to secure the implement therein; and a setting tool for said implement, comprising: a releasable connecting 70 75

- device for initially supporting said implement, a cylinder and piston therefor connected with said implement through said device, an electrically operated pump for supplying fluid under pressure to urge said piston in one direction from an initial position and cause movement of said elements in a manner to secure said implement, yieldable means tending to return said piston to its initial position, and an instrumentality operative upon return movement of said piston for releasing said device and disconnecting said setting tool from said implement. 5
8. The combination with an implement adapted to be lowered within a well bore and having elements capable of relative movement; of a tool structure, comprising: a releasable connecting device for initially supporting said implement, a cylinder and piston therefor connected with said implement through said device, means for supplying fluid under pressure to urge said piston in one direction relative to said cylinder and cause a predetermined movement of said elements, yieldable means tending to return said piston to its initial position, and an instrumentality operative upon return movement of said piston for releasing said device and disconnecting said tool structure from said implement. 10
9. The combination with an implement adapted to be lowered within a well bore and having elements capable of relative movement; of a tool structure, comprising: a releasable connecting device for initially supporting said implement, a cylinder and piston therefor connected with said implement through said device, an electrically operated pump for supplying fluid under pressure to urge said piston in one direction relative to said 15
- cylinder and cause a predetermined movement of said elements, yieldable means tending to return said piston to its initial position, and an instrumentality operative upon return movement of said piston for releasing said device and disconnecting said tool structure from said implement. 20
10. In a well tool; an implement adapted to be lowered within a well bore, and including elements adapted when moved relatively to secure the implement therein; and a setting tool for said implement, comprising: a connecting member, key means for securing said connecting member to one of said elements, a key retainer moveable to release said key means, a reciprocable thrust member moveable in one direction to urge the other element while the first element is restrained relative to said connecting member, and a clutch mechanism connected with said key retainer and engageable with said thrust member during its return movement to move said key retainer clear 25
- of said key means. 20
11. The combination with an implement adapted to be lowered within a well bore and having elements capable of relative movement; of a tool structure, comprising: a connecting member, key means for securing said connecting member to one of said elements, a key retainer moveable to release said key means, a reciprocable thrust member moveable in one direction to urge the other element while the first element is restrained relative to said connecting member, and a clutch mechanism connected with said key retainer and engageable with said thrust member during its return movement to move said key retainer clear 30
- of said key means. 35

ARTHUR J. ZSCHOKKE.
